CARDING MACHINE

Merritt L. Farrar, South Acton, Mass., assignor
to George M. Nay, Wellesley, Mass.

Application January 11, 1937, Serial No. 120,102

1 Claim. (Cl. 19—105)

The invention relates to a carding machine and more especially to a combined picking and carding machine.

The primary object of the invention is the provision of a machine of this character, wherein the same will open cotton thread in reworked wool and in this manner eliminating costly carbonizing processes which is necessarily required in mill work today and also will remove the sizing from all kinds of stock, especially rayon.

Another object of the invention is the provision of a machine of this character, wherein the use of a separate picking machine is avoided in that the picking and carding of the stock will be effected in one operation.

A further object of the invention is the provision of a machine of this character, wherein picking and carding will be executed on all kinds of stock, such as hair, wool, reworkable wool, silk and vegetable matter, namely, cotton, hemp, jute, flax, rayon, et cetera, and additionally mineral matter.

A still further object of the invention is the provision of a machine of this character, wherein in the same includes a minimum number of moving parts thus occupying the least possible floor space and assuring a maximum output.

A still further object of the invention is the provision of a machine of this character, which is comparatively simple in construction, thoroughly reliable and efficient in operation, assuring a picking and carding in a single working of the machine, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a side elevation of the carding machine constructed in accordance with the invention.

Figure 2 is an enlarged fragmentary vertical sectional view showing in detail the assembly of the carding cylinder, stock guide, guide roller and pressure roll embodied in the machine.

Figure 3 is a fragmentary perspective view of the stock guide.

Similar reference characters indicate corresponding parts throughout the several views in the drawing.

Referring to the drawing in detail, the machine

as usual comprises a frame A in which is journaled a main carding cylinder 5 having at its periphery the usual card clothing or Garnett wire 6 while carried by the frame A is a feeding and presser roll 7, its journal 8 at each end being supported in a shiftable bearing 9. The bearing fits in a guide way 10 and acting upon this bearing is a coiled expansion spring 11 suitably held in its working relation to said bearing. The presser roll 7 at its periphery as shown carries a rubber covering 12 although it may be otherwise surfaced, as for example with card clothing or Garnett wire. In other words, the cylinder 5 and the roll 7 may be covered at their peripheries with light materials or each of a composition. In this instance the roll 7 is covered with a rubber facing at its periphery.

Above the roll 7 is a guide roller 13 suitably journaled for the guiding of the stock 14 over the roll 7. The stock 14 is supplied to the machine between feed rolls 15, these being suitably journaled.

Supported next to the cylinder 5 and between it and the roll 7 is a stock guide bar 16, it having the concaved face 17 next to the cylinder 5 while another reversely concaved face 18 confronts the presser roll 7 and this guide bar functions to direct the stock 14 and to hold the same workable by the card cylinder 5. The bar 16 is stationary and the stock is forced past the lower edge 19 by the presser roll 7 which rotates clockwise and at a speed slower than the speed of rotation of the cylinder 5, the points of the clothing 6 of the latter being in the direction of rotation of the same and thus a direct carding action will be had on the stock 14 at the point of the edge 19 of the bar 16 and such stock will be picked up and have full carding action in a positive manner during the working of the machine in that the bar 16 firmly holds the stock for direct action by the cylinder 5.

The presser roll 7 acted upon at each end thereof by the spring 11 will be held closely against the knife edge of the stock guide between the presser roll and the cylinder 5 and this cylinder operates by rotation in the same direction with respect to the roll 7 but at a greater speed or rotation than the same. The stock in the feeding thereof is carried to the lower knife edge 19 of the bar 16 which is set the proper distance from the cylinder 5 and as the stock is forced past the bar the points of the clothing 6 of this cylinder co-operative with the knife edge 19 will work upon the stock, opening up the threads,

carding out the fibers and removing the sizing during the working of the machine.

The concaved faces 17 and 18 of the bar 16 effect at the lowermost portion of this bar the 5 knife-like edge 19.

What is claimed is:

A carding machine comprising a rotatable cylinder bearing card clothing, a feeding and presser roll mounted closely adjacent said cylinder, a 10 bar fixedly mounted and extending between said cylinder and roll having a knife edge extending

to substantially the line of closest approach of said cylinder and roll, said bar having a concave face adjacent said roll opening gradually outward therefrom away from said knife edge, and means for feeding material to the opening between said bar and roll, said roll mounted for movement radially with respect to said cylinder and having means for pressing it yieldingly toward said knife edge and cylinder. 5
